UNITED STATES PATENT OFFICE.

ANDY C. SHIPLEY, OF SPEEDWELL, TENNESSEE.

MUFFLER FOR FIREARMS.

971,083.

Specification of Letters Patent. Patented Sept. 27, 1910.

Application filed October 2, 1909. Serial No. 520,735.

To all whom it may concern:

Be it known that I, ANDY C. SHIPLEY, a citizen of the United States, and a resident of Speedwell, in the county of Claiborne 5 and State of Tennessee, have invented certain new and useful Improvements in Mufflers for Firearms, of which the following is a specification.

My invention relates to devices for preventing the noise incident to the discharge of a fire arm, and has for its object the provision of a chamber secured to the underside of the gun-barrel connected with the bore and provided with small openings at its forward end and with a plurality of disks adjacent to the forward end with unaligned openings to break up the discharge before reaching the small openings.

My invention will be described in detail 20 hereinafter and illustrated in the accompanying drawings, in which—

Figure 1 is a side view of a rifle showing my improved muffler in position thereon; Fig. 2, a longitudinal sectional view of the 25 muffler; Fig. 3, a cross-section on the line 3 of Fig. 2; Fig. 4, a cross-section on the line 4 4 of Fig. 2; and Figs. 5, and 6, detail views of the perforated members.

In the drawings similar reference characters indicate corresponding parts throughout the several views.

A indicates a rifle of my preferred construction and B the barrel.

As is well known the noise from the discharge of a fire arm is occasioned by the expansion of the gas of the charge at the muzzle of the arm, and my invention is designed to prevent all of the gas from escaping from the muzzle and consists in the provision of an expansion chamber connected 40 with the bore of the arm, which consists of the tubular casing 1, being a plurality of lengths of tubing 2, secured together by coupling-rings 3, the end tubes having their outer ends closed, as shown at 4. By constructing the casing in sections, as stated, it is capable of being dismembered periodically for cleaning.

The casing 1 is secured to underside of 50 barrel B by means of wedge-shaped projections 5 on coupling-rings 3, that engage wedge-shaped notches 6 in the barrel and through one of said projections, the one nearest the rear of the casing and intermediate the ends of the barrel, is provided 55 an opening 7 that alines with opening 7^a in

the barrel when the casing is in position. The underside of the forwardmost tube 2 is also provided with a wedge-shaped notch 8 to receive a block 9, having a wedge-shaped base 10 to engage the notch, said block being provided with an elongated socket 11, with holes 12 in its base connected with holes 13 cut transversely through the block, the casing being provided with an elongated slot 14 that alines with socket 11 when the block 9 is in position.

15 and 16 indicate disks secured in the forwardmost tube 2, disk 15 being notched around its edge, as shown at 17, to provide 70 openings for the passage of the gases of the discharge, while the disk 16 is formed with openings 18 for the same purpose, said openings being unaligned and having the function of not only retarding the escape 75 of the gas but also break its force so that when it reaches the block 9, through which it escapes, it passes out with a slight wheezing noise that is indistinguishable a short 80 distance from the marksman.

In operation as soon as the projectile passes the opening 7^a in the barrel the gas from the explosion enters the casing 1 and expanding therein passes through the openings 17 and 18 in disks 15 and 16, through slot 14 into socket 11 and thence through holes 12 and 13 to the outer air, a small portion of the gas following the bullet and escaping at the muzzle of the arm. As, however, the gas has expanded in the casing 1, it will be apparent that the report that usually accompanies the discharge of a rifle or other fire arm is effectually avoided and the position of the marksman unbetrayed to game or an adversary a short 95 distance away.

Having thus described my invention, what I claim is—

1. In combination with the barrel of a firearm, a tubular casing secured thereto and communicating with the bore thereof intermediate of the breech and muzzle, a block removably secured near the end of the casing, said block having a socket and a plurality of transverse holes communicating 100 with the socket, and the casing provided with a slot in alinement with the socket in the block, substantially as shown and described.

2. In combination with the barrel of a 110 firearm, a tubular casing removably secured thereto and communicating with the b

thereof intermediate between the breech and the muzzle, a block removably secured near the end of the casing and provided with a plurality of transverse holes communicating with the hole of the casing, and disks secured in the casing and spaced apart said disks being provided with unalined openings, substantially as shown and described.

In witness whereof, I have hereunto set my hand in presence of two disinterested 10 witnesses.

ANDY C. SHIPLEY.
